PLASTIC SHEET MATERIAL

Russel Wright, New York, N. Y.

Application April 15, 1958, Serial No. 50,484

Term of patent 14 years

(Cl. D87—3)

Fig. 1

Fig. 2

Figure 1 of the drawing is a plan view of one half of the repeating unit of my new design for a plastic sheet material and a portion of the adjacent unit. Figure 2 is a plan view of the other half of the repeating unit of the new design and a portion of the adjacent unit. Figures 1 and 2 joined at the broken lines at the bottom of Figure 1 and the top of Figure 2 form one complete repeating unit of the design.

I claim:
The ornamental design for a plastic sheet material, substantially as shown and described.
